Bartlett Rodin

Attorney

Patented July 22, 1924.

UNITED STATES PATENT OFFICE.

CURRY ORA WALPER, OF DETROIT, MICHIGAN, ASSIGNOR, BY DIRECT AND MESNE ASSIGNMENTS, TO STANDARD PLASTERING SYSTEM, OF DETROIT, MICHIGAN, A CORPORATION OF MICHIGAN.

COMPOSITION BOARD.

Original application filed August 20, 1921, Serial No. 493,921. Divided and this application filed July 24, 1922, Serial No. 576,970.

To all whom it may concern:

Be it known that I, CURRY ORA WALPER, a citizen of the United States of America, residing at Detroit, in the county of Wayne 5 and State of Michigan, have invented certain new and useful Improvements in Composition Boards, of which the following is a specification, reference being had therein to the accompanying drawings.

10 This invention relates to elements of building construction and has for its primary object the provision of a rigid panel of substantially fireproof material to be used in place of the usual wood or metal lath 15 and rough plaster for interior walls and ceilings, or in place of the various bases upon which stucco is applied to form exterior walls.

Another object of the invention is to 20 utilize a product hitherto considered as waste, as a building material for interior or exterior use, in constructing walls resistant to heat, at a cost considerably less than that of the materials now ordinarily employed.

25 A further object of the invention is to provide a wall board having a surface adapted for the proper adhesion of a finishing coat of plaster.

A still further object is the provision of a 30 finishing coat for a wall board adapted for adhesion to the board described herein and suited for easy application thereto as a smooth and fire resisting finish.

In the drawing, the figure represents a 35 transverse section of a fragment of a wall board embodying my invention.

In the preferred construction of wall board, a plastic composition is used consisting of the waste produce of asbestos manufacture 40 mixed with a suitable quantity of gypsum plaster. Asbestos occurs in veins of fibrous magnesium silicate. The surrounding rock is usually of a similar composition but is not so fibrous. After most of the 45 fibrous asbestos has been removed, the rock mined therewith containing some fibrous asbestos is usually discarded and considered as waste. It is sold in limited quantities as "rough asbestos" or "tailings." When this 50 "rough asbestos" is crushed, the resultant asbestos somewhat resembles a mixture of finely divided asbestos and talc. Mixed with a suitable plaster, such as the ordinary

"blue plaster" containing calcined gypsum and lime, from five to fifty per cent of the 55 plastic composition may consist of asbestos to form a suitable body for use as a fireproof wall board.

A composition of plaster and asbestos permits nails to be driven therethrough without cracking and by the use of nail sets, the heads may be countersunk and covered by the finishing coat for additional protection, yet the composition is so poor a conductor 60 of heat that a three-eighths inch board of 65 this material will prevent ignition of paper on the surface opposite a flame for a longer period than an inch thickness of ordinary plaster would.

Another waste product of asbestos manufacture is what is known as asbestos sandings, this material being the portion removed from the surface and edges of asbestos boards by grinding or sandpapering. This 70 waste material consists of asbestos fibers 75 and cement and is similar in its qualities to the crushed asbestos.

It is of course obvious that asbestos itself may be used with plaster to form a board of even better quality than that produced by 80 the use of asbestos or asbestos sandings.

This board having such a large percentage of asbestos is lighter than plaster for the same thickness, but since it is fireproof a 85 board may be used thinner than the ordinary plaster.

Another important advantage of the board possessing so high a percentage of asbestos 90 is the acoustic quality. Walls in which such boards are used will be less resonant than walls finished with a surface coating of hard plaster especially plaster containing a considerable percentage of calcined gypsum.

In order that a finishing coat may adhere 95 properly to the rough coat of a plastered wall or to a wall board there must be a certain suction. In other words the rough coat or wall board must be sufficiently porous to absorb some of the moisture from the finishing coat. If a rough coat or plaster board 100 is too porous the water will be withdrawn from the finishing coat so rapidly that not enough will remain for proper hydration of the gypsum contained in the finishing coat. If the rough coat or plaster board is not 105 sufficiently porous, the finishing coat will

set as a separate layer with very little adhesion to the rough coat or plaster board. In either case the finishing coat will be likely to crack and fall off.

- 5 To secure the proper adhesion, the degree of suction of the present wall board is regulated by the use of a size of casein or other suitable material applied to the surface of the wall board.
- 10 The mixture of crushed asbestic contains sufficient grit to obviate the necessity for the use of any sand when mixed with calcined gypsum and a suitable quantity of water to form a smooth flowing plastic composition. The boards may be molded of the desired thickness either in panels of a fixed length and width or as a continuous strip capable of being cut up at the factory into various commercial sizes. Before the
- 15 plastic composition has become set a sanding coat of coarse calcined gypsum is sprinkled over the surface absorbing a sufficient quantity of water from the wet composition to adhere and to form a very satisfactory surface for the adhesion of the finishing coat.
- 20 After the sanding coat has been applied the size of casein may be applied either while the board is still wet or after it has become dry and hard. In some cases it may be
- 25 preferred to apply the sizing of casein after the wall board is in position in a building structure.

The finishing coat will preferably consist of a fireproof composition consisting of crushed rough asbestos, calcined gypsum and lime. The function of the lime is to make the plastic composition easier of application as a smooth finishing coat, and in order to prevent too rapid setting of the

- 30 gypsum, a suitable quantity of commercial retarder may be used. While the present composition is resistant to compression when it has set, it is still capable of penetration by nails and their heads can be countersunk
- 35 almost as in wood.

It will be seen that the present material provides a plaster board much more highly resistant to heat than any other composition boards now in general use. The fact that

- 40 the crushed asbestic is at present a waste product enables the production of this board to be accomplished at a lower cost than many other wall boards.

This application is a division of my application filed August 20, 1921, Serial No. 493,921, Patent 1,448,886, Mar. 20, 1923.

The structure shown in the drawing illustrates a preferred form of wall board in which wire reinforcing fabrics are used ad-

jacent to the front and rear surfaces of the board as indicated by the reference numerals 1 and 2. Closely adjacent to the reinforcement is a nailing strip 3 preferably of sheet metal and preferably formed with projections 4 which are embedded within the plastic composition to form a key to prevent separation of the plastic center from the metallic back. The reinforcing strips are preferably secured to the backing 1.

It will be obvious that many modifications in the proportions of the various ingredients may be made within certain limits without sacrificing the advantages of the composition. I do not therefore wish to be limited to the exact percentages described, but desire to claim the invention in any of its modifications within the legitimate and valid scope of the following claims.

I claim:—

1. A wall board comprising a plastic composition containing crushed rough asbestic.
2. A wall board comprising a plastic composition containing crushed rough asbestic and gypsum plaster.
3. A wall board comprising a plastic composition containing from five to fifty percent crushed rough asbestic, and calcined gypsum.
4. A wall board comprising a plastic composition containing crushed rough asbestic and calcined gypsum, and having a surface layer of coarse calcined gypsum.
5. A wall comprising a layer of a plastic composition consisting of crushed rough asbestic and calcined gypsum and a layer consisting of a plastic composition of crushed coarse calcined asbestic, gypsum and lime.
6. A wall comprising a layer consisting of a plastic composition of crushed rough asbestic and calcined gypsum having an adhering second layer thereon of coarse calcined gypsum coated with casein and having a third layer adhering to the second, said third layer comprising a plastic composition of crushed rough asbestic, calcined gypsum and lime.
7. A structure as in claim 4 having a sizing coat of casein.
8. A wall board comprising a plastic composition containing crushed rough asbestic, calcined gypsum and metal.

In testimony whereof I affix my signature in presence of two witnesses.

CURRY ORA WALPER.
